UNITED STATES PATENT OFFICE.

EFFIE J. HUDSON, OF TEMPLETON, CALIFORNIA.

POULTRY-BROODER.

No. 836,259.

Specification of Letters Patent.

Patented Nov. 20, 1906.

Application filed December 20, 1904. Serial No. 237,735.

To all whom it may concern:

Be it known that I, EFFIE J. HUDSON, a citizen of the United States, residing at Templeton, in the county of San Luis Obispo and State of California, have invented a new and useful Poultry-Brooder, of which the following is a specification and description of the invention, such as will enable others skilled in the art to make and use the same.

My invention relates to an improvement in poultry-brooders, and particularly to brooders to be used without artificial heat and outside of any covered buildings; also to brooders for retaining the natural warmth of chicks and at same time permit them to breathe fresh air.

A further object of my invention is to provide a suitable pen adjoining the brooder-box, in which the chicks may exercise and feed and at the same time be under ready control.

I attain these and other objects by a device illustrated in the accompanying drawings, in which—

Figure 1 is a perspective view with a part of the brooder-box and pen cut out. Fig. 2 is a longitudinal section. Fig. 3 is a perspective view of the warming-cover removed from the brooder-box. Fig. 4 is a cross-section of the brooder-box and warming-cover suspended, a corner of the board floor cut out, and a corner of the flat cushion turned up. Fig. 5 is a view of feed-box or water-box and trough.

The brooder consists of a wooden box with a removable cover *a*, sloping slightly toward the back, which may be secured in place by eye-hooks passing through the cover, as *a'*, or by any simple means. The rear side *B* and the ends *b* are stationary, as is also the upper section of front side *b'*; but the lower section is left cut out for a doorway and is closed by a movable door *C* with any handle, as *r*, and is retained in place by perpendicular cleats *k*, one on the brooder-box and the other on the inner side of the pen-wall. The latter cleat also forms a support for one end of the rods for sliding partition hereinafter described. The door slips easily between the cleats.

The bottom of the box is made of coarse wire screen or netting *o*. Upon this netting is placed a removable board floor *p*, upon which is placed a removable flat cushion *L'*.

The board floor and flat cushion may be removed whenever the earth is not too cold or wet for chicks; and they can then benefit from contact with the earth by their feet resting thereon through the meshes of the netting, while vermin will be prevented from injuring the chicks by the size of meshes described.

The inner walls of the ends are provided with a series of bars *b²* *b³* of any desired number, upon which rests a wire-screen frame *h*, from which are suspended by a series of hooks and eyes a series of long roundish cloth cushions *h'*, stuffed with feathers or other suitable material for retaining the natural warmth of small chicks beneath. On the outer ends of these walls are canvas pouches *j* for retaining the superfluous cushions when removed from hooks in hot weather.

Adjoining the front of the box is a low rectangular pen *d*, attached to the box by side hooks and staples *m* or other simple means. The end contiguous to the box is open, corresponding with the doorway for door *C*. The other end and sides are constructed of light boards to protect the chicks from cold winds, yet by reason of their low height permitting sunshine to enter nearly every portion of the inclosure.

The pen may be constructed entirely of wire-netting in warm climate.

A suitable hand-hole and cover *d'* is provided in wire-netting top to permit ready control of the chicks by hand or for moving the cross-partition *d³*, slidably mounted on two parallel rods *d²*, attached to end of frame and cleats before described.

Near the bottom on both sides of the pen are openings *f* to receive a portion of a feed or water trough. Fig. 5 represents such a trough being a portion of a box, which is connected to the sides of the pen by any simple means, as hooks *n*, dropping into screw-eyes in the said sides. The top or cover of this box may be fixed to raise on hinges or be otherwise readily moved to permit placing therein food or water. The lower and protruding portion of the box forms a trough *g*, which reaches through into the pen and from which the chicks feed or drink, but cannot stand therein by reason of the narrow space. The high sides of the feed-box above the troughs retain sufficient supply of feed to satisfy the chicks all day, the feed falling

down into the trough as the chicks feed and the sides also preventing outside fowls from stealing the food or drink.

In use the chicks as soon as hatched are placed in the brooder-box under the suspended cushions and upon the flat floor-cushion, door C is left open, and the chicks permitted to run out in the pen as soon as they desire and to there remain all day standing directly upon the earth, except when the ground is too cold or wet, when a board platform may be placed under the pen, as the cover *a* from the brooder-box. Tiny chicks may be limited in space by adjusting the partition *d*³ and may also be forced into the brooder-box by same partition and retained therein at night by dropping the door C into place.

The long cushions are suspended in parallel lines or rows from the warming-screen cover and in cold weather are hung so closely that their sides touch, with their lower surfaces at such a height that the backs of the chicks will just nicely reach the same. The height of the warming-cover is determined by the supporting parallel bars *b*² *b*². When it is desired to move the cover suspending the cushions, one side thereof is raised first, which will permit that side to pass the next higher bar, when the whole warming-cover may be raised to the desired bars and dropped into place in a similar manner, one side first.

A series of ventilating-holes *i* are arranged along the tops of the end walls of the brooder-box just beneath the cover *a*, and it is found that the heated air from the lungs of the chicks readily rises above the suspended cushions from around their sides and between them as suspended and passes out through the holes described, and fresh cool air takes its place for breathing.

An apron *e* is provided for the lower sides of the pen to hang down and conform to uneven places in earth for a wall.

It is found that the natural warmth of the chicks will be retained to such an extent by the suspended cushions resting upon the backs of the chicks and the flat cushion beneath their feet that no artificial heat is required in the coldest weather. In very hot weather the warming-cover may be raised to top of box and form barrier from the sun during the day, and the board cover *a* is seldom required, except in rainy weather. When the nights are very warm, it is desirable to remove part of the suspended cushions from their simple hooks and deposit the same in the pouches *j*.

The feather cushions suspended are light and can be readily raised by the chicks as the feathers of a hen, while at the same time retain the natural warmth. The chicks soon learn to sleep with their backs under the suspended cushions, while their heads and nostrils protrude out around from under the cushions and even up between the rows there-

of, thus keeping their bodies warm and breathing fresh air. This device has been found to be superior to natural mothers, and the chicks very quickly learn to go under the suspended cushions at night without aid. The suspended cushions and under flat cushion are readily washed and dried, and the lower cushion may be kept clean by frequently renewing a thin cover of paper or cloth, thus insuring healthy chicks.

Various attempts have been made to provide a brooder that would take the place of the natural mother as does my device, but by reason of their complicated construction, lack of ventilation, and necessity for artificial heat have not been found practicable.

Having thus fully described my invention, what I claim as new is—

1. A poultry-brooder, consisting of a pen provided with a screen-roof and hand-hole 85 therein and cover therefor, two parallel rods, a sliding partition on rods, detachable feed boxes and troughs, apertures in sides of the pen to receive trough portions of the boxes; together with a brooder-box and solid cover 90 therefor, a wire bottom thereto beneath a removable wooden floor, supporting a flat cushion; a removable screen-frame suspending a series of long cushions stuffed with feathers, bars to retain said frame, pouches to retain 95 superfluous cushions, a removable door between the box and pen, substantially as shown and described.

2. A brooder consisting of a rectangular pen, provided with a hand-hole in the top, 100 and having or provided with apertures in the sides, detachable feed boxes and troughs, an apron around the lower edge of the pen-frame, two parallel rods, a partition slidably mounted on the rods, and one end of the 105 pen opening into a brooder-box contiguous thereto, substantially as shown and described.

3. A brooder, consisting of a box with a removable sloping solid cover, two stationary 110 ends, a stationary back, a front end the upper portion being stationary and a door occupying the lower portion thereof, a series of bars attached to the inner walls of the ends, a movable frame supported by the bars and 115 provided with a series of hooks extending downward, long cloth cushions stuffed with feathers suspended from hooks by eyes engaging the same, pouches on outer ends of the box, a wire-screen bottom, a removable 120 wooden floor, a removable flat cushion supported by said board floor, with a rectangular pen attached to the front side of said brooder-box, substantially as shown and described.

4. A brooder comprising a box with interior bars, a warming cover or frame resting on said bars, a series of long removable cloth cushions stuffed with a soft light bad heat-conductor substance suspended from said 130

warming-cover, a wire-screen floor and a removable wooden floor, with a removable flat cushion resting upon said board floor, substantially as shown and described.

5. A brooder with a warming frame or cover made of a series of removable long cloth cushions stuffed with a soft light bad heat-conductor substance hung up parallel

on the under side of said frame, substantially as shown and described.

In testimony whereof I hereunto affix my signature in presence of two witnesses.
